OIL DISPENSING DEVICE

William F. Punte, Syracuse, N. Y., assignor to
 Continental Can Company, Inc., New York,
 N. Y., a corporation of New York

Application November 28, 1933, Serial No. 700,123

6 Claims. (Cl. 221—23)

The invention relates to new and useful improvements in a device for opening and dispensing oil from hermetically sealed cans.

An object of the invention is to provide a simple form of dispensing device which is adapted to receive an end portion of the can and form a dispensing opening in the side wall thereof close to the double seam.

A further object of the invention is to provide an oil dispensing device of the above type wherein in the cutter for severing the side wall of the can is mounted in an extension of the body of the dispensing device and wherein said extension is also provided with a spout for directing the flow 15 of oil from the can.

A still further object of the invention is to provide a dispensing device of the above type wherein in the cutter is so constructed that the oil flowing from the can passes through said cutter into 20 said spout.

These and other objects will in part be obvious and will in part be hereinafter more fully disclosed.

In the drawings—

25 Fig. 1 is a side view of the oil dispensing device showing the position of the same when applied to a can for the severing of the wall of the can;

30 Fig. 2 is a similar view with the dispensing device shown in section and the cutter having been operated for cutting the wall of the can;

Fig. 3 is a face view of the dispensing device looking into the chamber thereof with the cutter advanced;

35 Fig. 4 is a sectional view on the line 4—4 of Fig. 2;

Fig. 5 is a view partly in section showing the can in the dispensing device with the wall thereof cut and the dispensing device positioned for 40 discharging the contents of the can into the chamber where it is to be used for lubricating purposes;

Fig. 6 is an enlarged perspective view of the cutter with parts broken away to show the inner structure;

45 Fig. 7 is an enlarged view of a portion of an hermetically sealed can which has been opened by the oil dispensing device, and with parts in section to show the relation of the opening to the double seam of the can, and

50 Fig. 8 is a side view of the lower portion of the can.

It is a common expedient to package liquid products in hermetically sealed cans consisting of a body portion with ends double-seamed thereto. The product marketed in such cans is not

only protected from contact with the air, but the contents of the can cannot be changed without giving physical evidence of the can having been tampered with. Lubricating oil is being put up by the original dispensers in sealed cans and sold at filling stations where they may be opened in the presence of the customer and emptied into the chamber where it is to be utilized for lubricating purposes. This insures that the customer obtains the original product. The present invention has to do with a device for opening and dispensing liquid from an hermetically sealed can.

Oil dispensing devices are being used which are in the form of a funnel having a cutter for cutting an opening in the end wall of the can. Such a dispensing device is very satisfactory, but it permits the unscrupulous dealer, after a can has been emptied, to sever the body wall below the double seam, reflare the wall of the can body, fill the can with an inferior product and then attach and double seam the end to the can. The present invention is directed to a type of oil dispensing device wherein the can is opened by a cutter which penetrates the side wall of the can and this will prevent any such use of the can as above described.

In carrying out the invention, a dispensing device has been provided which includes a body having a bottom member 1 and side walls 2 forming a chamber 3 which is shaped to conform to the end portion of an hermetically sealed can. Such a can is indicated at 4 in the drawings. The can has an end 5 secured to the body portion thereof by a double seam 6. It also has the other end 90 closed by an end portion secured to the body by a double seam 7. This is the standard form of can used for hermetically sealing and for marketing liquid products. The can is cylindrical in cross section, and the chamber is likewise cylindrical and is of such dimensions as to receive freely the double seam which projects slightly beyond the wall of the can body.

The body of the dispensing device is provided with an extension 8 which is arranged so that 100 its longitudinal axis passes through the center of the chamber. The extension is provided with a passage therethrough indicated at 9. This passage extends longitudinally of the extension and into the chamber 3. The extension has a bottom portion with which is integrally formed side walls 10, 10. These side walls 10, 10 are connected by a cover plate 11 secured to the side walls by suitable screws 12, 12. This forms the passage 9 which, as noted, extends longitudinally through 110

the extension. Carried by the bottom wall of the extension is a pouring spout 13. As shown, this pouring spout is formed integral with the extension. It may, however, be made separate and attached thereto, but it is preferably rigidly attached to the extension and forms a rigid extension thereof. Said spout inclines away from and outward from the bottom 1 of the dispensing device.

- 10 Located in the passage 9 is a cutter 14. Said cutter is tubular and preferably rectangular in shape. The cutter is dimensioned so that it completely fills the passage 9, closing the outer end of the passage. At the outer end of the cutter 15 is a head 15 which projects beyond the side walls of the cutter. The cutter is provided with a piercing point 16, and with cutting edges 17, 17 leading laterally therefrom in the bottom wall 18 of the cutter. Extending upwardly and rearwardly 20 from the inner ends of the cutting edges 17, 17, are cutting edges 19, 19. These are formed in the side walls of the cutter. This piercing point is at the lower side of the cutter.

The cutter is mounted for endwise movement 25 in the passage 9, and the extent of movement of the cutter is limited by a pin 20 which extends into a slot 21 formed in the upper wall of the extension. The cutter is provided with an opening 22 in the lower wall thereof. Disposed in the 30 rear portion of the cutter is a filler or core 23, the inner wall 24 of which is inclined. This opening 22 in the cutter, when the cutter is moved all the way in, is in alignment with the spout, and there is a continuous passage through the cutter 35 into the spout. The cutter when retracted is completely housed within the extension, and the piercing point does not project into the chamber 3. At this time the end portion of the can is placed in the chamber preparatory to the severing 40 of the side wall thereof.

The side wall of the dispensing device opposite the extension is laterally extended and shaped so as to provide a supporting base 25. This supporting base is also laterally extended a distance 45 slightly greater than the length of the can which is to be placed in the dispenser, as indicated at 26. At the outer end of this lateral extension of the base there is an upstanding portion 27. The inner face of the base is curved to conform to the curvature of the can body, and said extension of the base is preferably cut away so as to lighten the same. The end of the can body to be pierced is placed in the body portion of the dispensing device and on this extension of the base, and the 50 base is placed on a solid foundation. The cutter is then forced downward by hand pressure or by foot pressure, thus causing the piercing point to penetrate the wall of the can body and to cut said wall along the double seam, as indicated at *a* in Fig. 8, thence along parallel lines *b*—*b*, thus forming a relatively large opening as indicated at *c*. The metal which is cut from the body wall is rolled inwardly and upwardly as indicated at *d*. The cutter is provided with an opening 27 which is just inside the can wall when the cutter is at the forward end of its movement. After the dispensing device has been attached to the can and the wall thereof cut, it is then turned to the position shown in Fig. 5, and the oil will flow freely 60 through the opening *c* into the cutter and through the cutter into the spout, and thus be discharged into the passage 28 leading to the chamber where it is to be used for lubricating purposes. It will readily be seen that after the spout is placed in the passage, it will support the dispensing device

and the can so that the operator may leave the can to drain while other matters are being attended to. The spout inclines outwardly and away from the bottom, so that when it is placed in the passage leading to the chamber where the oil is to be used, the bottom wall 1 of the dispensing device will be inclined and will, therefore, incline the can, so that all of the contents of the can will drain from the opening formed in the side wall thereof. Any oil passing beneath the cutter will find its way through the opening 22 into the spout.

When the cutter is forced through the side wall of the can, it will hold the can firmly seated in the dispensing device and on its rest on the supporting base. As long as the cutter remains in the can, the can and the dispensing device are united as a unit and may be handled as such. The cutter remains in the can during the dispensing of the oil, and the oil is dispensed through the cutter. This, together with the fact that the opening through the cutter and through the spout is of sufficiently large dimensions to carry away the oil flowing from the opening formed, enables a very short body wall 2 to be provided which only extends a slight distance above the opening formed in the can wall. This produces a very simple and light dispensing device which can be readily handled. The dispensing device is not only light, simple in construction, and of few parts, but it may be quickly attached to and removed from a can. Furthermore, when the dispensing device is attached to a can, the oil is quickly dispensed through the opening formed in the side wall of the can without any resulting spill.

It is obvious that minor changes in the details of construction and the arrangement of the parts may be made without departing from the spirit of the invention as set forth in the appended claims.

Having thus described the invention, what I claim as new and desire to secure by Letters Patent, is—

1. An oil dispensing device for hermetically sealed cans comprising a body having a bottom member and side walls forming a chamber shaped to conform to the end of the can, said body having an extension at one side thereof provided with a passage therethrough leading to said chamber, a spout carried by said body and communicating with said passage, a cutter mounted for endwise movement in said passage, said cutter having a body portion for closing the outer end of said passage, and a cutting point at its lower side with cutting edges leading away from and upwardly from the cutting point for cutting an opening in the side wall of the can and rolling upward the cut-away portion, said cutter having a passage therethrough connecting with said spout whereby the oil from the can may be dispensed through the cutter into the spout.

2. An oil dispensing device for hermetically sealed cans comprising a body having a bottom member and side walls forming a chamber-shaped to conform to the end of the can, said body having an extension at one side thereof provided with a passage therethrough leading to said chamber, said body having a base at the opposite side from said extension on which said dispensing device may rest during the penetrating of the side wall of the can, a spout carried by said body and communicating with said passage, a cutter mounted for endwise movement in said passage, said cutter having a body portion for closing the outer

- end of said passage, and a cutting point at its lower side with cutting edges leading away from and upwardly from the cutting point for cutting an opening in the side wall of the can and rolling upward the cut-away portion, said cutter having a passage therethrough connecting with said spout whereby the oil from the can may be dispensed through the cutter into the spout. 5
3. An oil dispensing device for hermetically sealed cans comprising a body having a bottom member and side walls forming a chamber shaped to conform to the end of the can, said body having an extension at one side thereof provided with a passage therethrough leading to said chamber, a spout carried by said body and communicating with said passage, a cutter mounted for endwise movement in said passage, said cutter having a body portion for closing the outer end of said passage, and a cutting point at its lower side with cutting edges leading away from and upwardly from the cutting point for cutting an opening in the side wall of the can and rolling upward the cut-away portion, said cutter having a passage therethrough connecting with said spout whereby the oil from the can may be dispensed through the cutter into the spout, said cutter operating when in its forward position in the can to secure said can to said dispensing device. 10
4. An oil dispensing device for hermetically sealed cans comprising a body having a bottom member and side walls forming a chamber shaped to conform to the end of the can, said body having an extension at one side thereof provided with a passage therethrough leading to said chamber, a spout carried by said body and communicating with said passage, a cutter mounted for endwise movement in said passage, said cutter having a body portion for closing the outer end of said passage, and a cutting point at its lower side with cutting edges leading away from and upwardly from the cutting point for cutting an opening in the side wall of the can and rolling upward the cut-away portion, said cutter having a passage therethrough connecting with said spout whereby the oil from the can may be dispensed through the cutter into the spout, the wall of the chamber opposite said extension being shaped so as to form a flat supporting base, and said base being extended so as to form a recess and support for the can body. 15
5. An oil dispensing device for hermetically sealed cans comprising a body having a bottom member and side walls forming a chamber shaped to conform to the end of the can, said body having an extension at one side thereof provided with a passage therethrough leading to said chamber, the lower wall of said passage being substantially parallel with the inner wall of the bottom member and spaced away therefrom the thickness of the double seam, a spout carried by said body and communicating with said passage, a cutter mounted for endwise movement in said passage, said cutter having a bottom wall contacting with the bottom wall of said passage, said bottom wall of the cutter being provided with a piercing point and cutting edges for severing the can along and close to the double seam, said cutter having parallel cutting edges for cutting the body wall along spaced parallel lines, the inner end of said cutter having a passage therethrough connecting with an opening leading from the wall of the cutter registering with the spout when the cutter is at the forward end of its movement. 20
6. An oil dispensing device for hermetically sealed cans comprising a body having a bottom member and side walls forming a chamber shaped to conform to the end of the can, said body having an extension at one side thereof provided with a passage therethrough leading to said chamber, the lower wall of said passage being substantially parallel with the inner wall of the bottom member and spaced away therefrom the thickness of the double seam, a spout carried by said body and communicating with said passage, a cutter mounted for endwise movement in said passage, said cutter having a bottom wall contacting with the bottom wall of said passage, said bottom wall of the cutter being provided with a piercing point and cutting edges for severing the can along and close to the double seam, said cutter having parallel cutting edges for cutting the body wall along spaced parallel lines, the inner end of said cutter having a passage therethrough connecting with an opening leading from the wall of the cutter registering with the spout when the cutter is at the forward end of its movement, the inner wall of said chamber opposite said extension being shaped so as to form a flat supporting base, and said base being extended so as to form a recess and support for the can body. 25
